UNITED STATES PATENT OFFICE.

NEWTON ROGERS, OF TERRE HAUTE, INDIANA, ASSIGNOR OF TWO-THIRDS
TO JOSEPH H. BLAKE AND JAMES WHARRY, OF SAME PLACE.

DRIVING MECHANISM FOR STREET-CARS.

SPECIFICATION forming part of Letters Patent No. 350,017, dated September 28, 1886.

Application filed April 19, 1886. Serial No. 199,303. (No model.)

To all whom it may concern:

Be it known that I, NEWTON ROGERS, of Terre Haute, in the county of Vigo and State of Indiana, have invented certain new and useful Improvements in Mechanism for Transmitting Power; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to devices for transmitting the power derived from an engine to machinery, and has relation especially to devices for transmitting the power of a gas-engine to the axle of a street or other car, although it may be applied with good results to many other purposes.

It has for its especial object to furnish a dummy which shall carry a gas-machine for generating a sufficient supply of gas by any well-known process of generating, a gas-engine which shall receive its supply of gas from the aforesaid gas-machine, and suitable mechanism whereby the power of said gas-engine shall be effectually utilized and transmitted to the running-gear of the car; and with this object in view my invention consists in the improved construction, arrangement, and combination of parts hereinafter fully described, and afterward specifically pointed out in the claims hereto annexed.

In the accompanying drawings, Figure 1 is a top plan view of a car-truck provided with my improved power-transmitting mechanism, in which is also shown, by dotted lines, the position in which the gas-generating machine and the gas-engine may be placed. Fig. 2 is a sectional view taken on the vertical plan x of Fig. 1, looking in the direction of the arrow. Fig. 3 is a sectional view taken on the vertical plan y of Fig. 1. Fig. 4 is a bottom plan view of a part of the devices shown in Fig. 1, showing especially the shifting or reversing mechanism; and Fig. 5 is a sectional view taken on the vertical plan z of Fig. 1, one end of said section, on the right, being partly broken away. Fig. 6 is a detail

sectional view showing the dovetail block K' , having groove k' , and the blocks to which the bearings H H' are secured, fitting in said grooves.

Like letters of reference mark the same parts wherever they occur in the several figures of the drawings.

Referring to the drawings by letters of reference, A A' are the end frame pieces or sills of the truck of a car, a a' the longitudinal beams or sills, and a'' an inner longitudinal beam, stringer, or sill, all of which parts may be of any suitable timber, and of a size to be regulated by the weight to be borne by them, and the judgment of the car-builder.

B B' are the axles, carrying wheels b b' and b'' b'' , and mounted in suitable bearings, B B' , suspended in this instance below the longitudinal beams a a' by means of suitable bolts, b b' . The axles B B' extend beyond the wheels, and, after the manner of the driving-wheels of a locomotive, are provided on each end with cranks C , wrist-pins C' , and parallel connecting-rods C'' , whereby they are caused to rotate in unison with each other.

D is another shaft, mounted in suitable bearings, D' , located on top of the stringers or sills a , a' , and a'' . This shaft is provided with a crank, d , to receive the pitman d' of a gas-engine, which may be located in either the position shown by dotted lines at E or that similarly shown at E' , which engine receives its gas-supply from a gas-generator by means of suitable piping, (not shown,) which gas-generator may be located in any suitable position, as shown by the dotted lines at F or F' , preference being given to the opposite end of the car from that on which the engine is located, for the purpose of suitably distributing the weight and ballasting the car.

On the shaft D , I mount a double-bevel friction-gear, G , which I prefer to make of paper, although this material may be varied, which engages with two bevel friction-gears, G' , preferably made of metal, which are mounted upon the ends of two shafts, H H' , lying in a slightly-inclined position and at right angles to the shaft D , and are mounted in suitable bearings, H H' , as hereinafter explained. On the opposite ends of these shafts H H' are mounted

bevel friction-gears I I, similarly shaped and of the same material as the gears G'.

On the axle B', I mount a central double-bevel friction-gear, I', and two single-bevel friction-gears, I" I", also preferably made of paper, which, as will be set forth further on, engage with the bevel friction-gears I on shafts H. Each of these shafts H H is provided with a universal joint, h, and a longitudinal slip-joint, h'.

In order to keep the gears G' G' properly in contact with the double gear G, and in order to cause the gears I I to engage the double gear I' or the single gears I" I", as desired, the bearings H' H' and H" H", in which both ends of the shafts H H are mounted, must necessarily all be adjustable laterally. Each of these bearings is therefore provided with a dovetail projection or rib, h", on its under side, which has a bearing in a suitable dovetail groove in a laterally-extending pedestal-block, that block on which the bearings H' H' are mounted being marked K and its dovetail groove k, and that in which the bearings H" H" are mounted is marked K' and its groove k'. Each of the dovetail projections h" on the bearings H' H' is perforated to receive a rod, i', which passes through said perforations, extending far enough on either side to serve as a bearing upon which spring i" is coiled, and which bear, respectively, against the outer sides of the bearings H' H' and nuts i and i''', which are threaded upon the ends thereof, and serve to regulate the pressure of the spring against the bearings, a block, i''', with a plain bore, being interposed between the nut i''' and the spring, the other nut, i, (on the right hand of Fig. 5,) being, as is also the block i''', accurately shaped to fit and move in the dovetail groove k in block K. By screwing up the nut i''' there is set up and maintained a spring or yielding contact between the gears G and G' G", which can be very readily regulated at will.

The bearings H" H", as before stated, are provided with dovetail blocks to fit a groove, k', in block K', similar to the dovetail blocks shown in section in Figs. 3 and 5; but they are, however, moved by the following mechanism: L L' are two bars having, similarly to the shafts H H, slip-joints h' h', and which are connected at their ends by bearings l l and l' l', to the shaft D and axle B, respectively, so that said shaft and axle turn freely therein. These bars L L' serve as supports for the dovetail bars K K'. On K', I mount a pivot, m, having a disk, m', on its upper end and its lower end squared, said disk m' being provided with two wrist-pins, to which are pivoted the ends of connecting-rods m'', their opposite ends being connected to the bearings H" H" by suitable pivots. On the lower square end of the pivot m (see Fig. 4) is mounted a rod, n, pivoted at its outer end to a connecting-rod, n', similarly pivoted at its opposite end to the arm n" of the elbow-lever pivoted at n''' to the under side of bar L. The other arm, N, of this elbow-lever is pivoted to a rod, N', which

has at its opposite end a fork, o, in which is pivoted the lower end of a hand-lever, o', said hand-lever being pivoted at o" to a block on the bar L. Its upper end is provided with a handle, P, and spring-pawl p, which pawl, at its lower end, engages the teeth of a segment-rack, p', secured to any stationary parts of the machinery. By means of this hand-lever and its connections the bearings H" H" are simultaneously moved inward and outward toward or from each other, carrying the gears I I with them, and bringing said gears alternately into contact with either the double gear I' or the gears I", accordingly as it may be desired to cause the car to run forward or backward. This adjustment laterally of these ends of shafts H while the opposite ends remain stationary would be impossible but for the provision of the universal joints h in the shafts H H; hence this provision.

As it will be necessary to mount the truck on springs which are in the axle-bearing boxes, but which I consider it unnecessary to show, as the car moves along the track there will be a vertical movement of the shaft D with relation to the car-axle B. Every motion of this kind tends to lengthen and again shorten the distance between said axle and the shaft. To accommodate this motion is the purpose of the slip-joints in the shafts H H and the bars L L', and without such or some equivalent provision the whole device would be inoperative and liable to be broken at the first attempt to use it.

Having thus fully described my invention, what I claim, and desire to secure by Letters Patent of the United States, is—

1. In combination with the frame of a car-truck, an axle mounted thereon and having the friction-gears I' I", the two shafts at right angles to the axle and carrying friction-gears I and G', said shafts being adjustable to bring the gears G' G' nearer to or farther from each other, and having universal joints h, and the shaft D, mounted in the frame and provided with friction-gear G, as set forth.

2. In combination, the shaft D, having friction-gear G, the shafts H, having gears G' and I, slip-joints h', and universal joints h, and being adjusted laterally, as set forth, and the axle B', having gears I' I", and mounted in spring-bearings, as set forth.

3. In combination, the shaft D, having double gear G, the shafts H H, carrying gears G', the bearings H' H', provided with dovetail projections, the dovetail grooved bar K k, the bar i', springs i'', and nuts i and i''', as set forth.

4. In combination, the axle B', having double gear I' and two gears, I", the shafts H H, carrying gears I, the bearing-block H", having dovetail projections, the bar K', having dovetail groove k' to receive said projections, and the system of levers connected with said bearing-blocks, whereby they are moved and the gears I caused to engage either the gear I' or the two gears I' I", as desired.

5. In combination, the shaft D, the axle B', mounted in spring-bearings, intermediate mechanism whereby motion is communicated from the shaft to the axle, and the bars L L',
5 provided with slip-joints h', and mounted by means of bearings l l' upon said shaft and axle, as set forth.

In testimony that I claim the foregoing as my own I hereto affix my signature in presence of two witnesses.

NEWTON ROGERS.
